CLAIM

The ornamental design for a lug nut remover, as shown and described.

DESCRIPTION

FIG. 1 is a left front perspective view of a lug-nut remover showing my new design;

FIG. 2 is a right end elevational view; and

FIG. 3 is a left end elevational view thereof;

The undisclosed side portions of the lug-nut remover are the same in appearance as side portions shown in FIG. 1.

FIG. 1

FIG. 2

FIG. 3
